UNITED STATES PATENT OFFICE.

WASEL KREKLEWICZ, OF HAIRY HILL, ALBERTA, CANADA.

DESIGN FOR A HOE.

57,057.

Specification for Design.

Patented Feb. 1, 1921.

Application filed August 6, 1920. Serial No. 401,797. Term of patent 7 years.

To all whom it may concern:

Be it known that I, WASEL KREKLEWICZ, a citizen of Ukraine, residing at Hairy Hill, in the Province of Alberta and Dominion of Canada, have invented a new, original, and ornamental Design for a Hoe, of which the following is a specification, reference being had to the accompanying drawing, forming part thereof.

The figure is a view in perspective of a hoe, showing my new design.

I claim:

The ornamental design for a hoe, as shown.

WASEL KREKLEWICZ.
